UNITED STATES PATENT OFFICE

122,317

DESIGN FOR A COMBINED ASH TRAY AND CIGARETTE REST

Edward F. McDonald, Buffalo, N. Y., assignor
to McDonald Products Corporation, Buffalo,
N. Y.

Application February 23, 1939, Serial No. 83,156

Term of patent 14 years

To all whom it may concern:

Be it known that I, Edward F. McDonald, a citizen of the United States, residing at Buffalo, in the county of Erie and State of New York, have invented a new, original, and ornamental Design for a Combined Ash Tray and Cigarette Rest, of which the following is a specification, reference being had to the accompanying drawing, forming part thereof.

The figure shows a perspective view of a com-

bined ash tray and cigarette rest, showing my new design, the ash tray being shown in broken lines.

The dominant feature of my design resides in the portion shown in solid lines.

I claim:

The ornamental design for a combined ash tray and cigarette rest, as shown and described.

EDWARD F. McDONALD.
